US0D1105126S

(12) **United States Design Patent** (10) Patent No.: **US D1,105,126 S**
(45) Date of Patent: ** Dec. 9, 2025

(54) **DISPLAY SCREEN OR PORTION THEREOF WITH GRAPHICAL USER INTERFACE**

(71) Applicant: **Fusion Holdings Limited**, Douglas (IM)

(72) Inventors: **Boris Mitskevitsh**, Tallinn (EE); **Artur Piel**, Tabasalu (EE)

(73) Assignee: **Fusion Holdings Limited**, Douglas (IM)

(**) Term: **15 Years**

(21) Appl. No.: **29/967,130**

(22) Filed: **Oct. 8, 2024**

(51) LOC (15) Cl. **14-04**

(52) U.S. Cl.

USPC **D14/485**

(58) **Field of Classification Search**

USPC D14/485-495

(57) **CLAIM**

The ornamental design for a display screen or portion thereof with graphical user interface, as shown and described.

DESCRIPTION

The FIGURE is a front view of a display screen or portion thereof with graphical user interface showing our new design.

The outer perimeter shown in broken lines illustrates a display screen or portion thereof and forms no part of the claimed design. The remaining broken lines illustrate portions of the graphical user interface that form no part of the claimed design.

1 Claim, 1 Drawing Sheet
